SIREN

Olof Ingemar Harald Ekman, Stockholm, Sweden

Application July 2, 1934, Serial No. 733,497
In Sweden March 21, 1934

7 Claims. (Cl. 116—147)

This invention relates to sound producing devices particularly sirens, of the type comprising a blade wheel or rotor and a surrounding casing or stator formed with sound openings, through which air is driven out at intervals by the rotating blade wheel so as to produce the sound in the well-known way. The invention relates more specifically to sirens of this type which are adapted to throw the sound in a definite direction or directions or in varying directions. An object of the invention is to provide a siren of this kind which is efficient in operation and simple in construction.

One feature of the invention involves the provision of means, by which only one blade or a few blades of the rotor is or are allowed to operate at a time so that substantially the entire effect of the driving motor will be utilized in expelling air from this blade or blades. To this end the casing is provided with a wall or partition covering the inlet to the blade wheel and having an opening therein which cooperates with the blades of the wheel for controlling the flow of the air through the device, for instance, by admitting air to a certain part of the blade wheel only at any given time.

In order that in a siren of this type the entire effect of the driving motor may be utilized by one blade or by only a few blades at a time, the blades of the rotor must be made larger than the blades of a siren built for the same effect, but in which admission of air takes place to the entire blade wheel at the same time, and in which the sound is simultaneously thrown in all directions, or the speed of the rotor must be increased at unchanged size of the blade wheel. This is true especially in case of sirens, in which the emission of the sound takes place through a single sound opening or through a single amplifying horn. As the driving motor, as a rule, runs at its maximum speed, it will be necessary in order to satisfy the above said condition to increase the radial or axial length of the blade wheel or both these lengths. Such an increase, however, must be very great, if the emission of the sound takes place through a single horn from one sound opening in the casing or from only a few sound openings. Another object of the invention is, therefore, to provide means for obtaining an increased efficiency of the blade wheel, without increasing its dimensions or speed, or with a very small increase of these factors. To this end I provide in front of the wall or partition covering the inlet of the blade wheel a receiver for the compressed air.

In the accompanying drawings several embodiments of the invention are illustrated in a substantially diagrammatic manner. Fig. 1 is a side elevation, partly in section, of a siren comprising a rotor and a stator. Fig. 2 is a top plan view of Fig. 1. Fig. 3 is a horizontal section of the siren, the section being taken with the object in view of showing the blade wheel. Fig. 4 is an axial section of a siren having a rotary compressor and a receiver for the compressed air. Fig. 5 is a horizontal section on the line V—V of Fig. 4. Fig. 6 is a diagrammatic section of the blade wheel of the apparatus shown in Fig. 4. Fig. 7 is an axial section of an apparatus like that of Fig. 4, but provided with a conduit for restoring air to the inlet of the compressor from the parts of the blade wheel not in operation. Fig. 8 is a cross section on the line VIII—VIII of Fig. 7. Fig. 9 is an axial section of a modified embodiment having a radial flow compressor and a receiver for the compressed air. Fig. 10 is a cross section of this apparatus. Fig. 11 is a detail view. Fig. 12 is an axial section of a modified form of the apparatus shown in Fig. 7, and Figs. 13 and 14 are cross sections on the lines XIII—XIII and XIV—XIV, respectively of Fig. 12.

With reference to Figs. 1—3, the numeral 1 indicates the driving motor, the shaft 2 of which carries the blade wheel. The blade wheel comprises a circular disk 3 attached to the shaft 2 which carries a number of blades 4. As shown in Fig. 3, the blades 4 are shaped as hollow sectors, closed at all sides, which form peripherally open sector-shaped spaces between them. The blade wheel is surrounded with a very little clearance by a wall 5 carried by the frame of the motor 1 which is formed with a plurality of openings 6 corresponding in size and number to the spaces of the blade wheel. Above the blade wheel, the wall 5 carries an end wall 7 covering the inlet of the blade wheel with the exception of a small inlet opening 8. Said opening may, preferably, as shown in Fig. 2, be shaped as a sector corresponding to the space between each two blades of the blade wheel. It is to be noted that the shape and number of blades and openings may be varied arbitrarily.

In the rotation of the blade wheel, air enters through the opening 8, as soon as a space of the blade wheel comes into register with said opening. This air will then be expelled at a high speed through the nearest opening 6, thereby producing sound in well-known way. The remaining openings 6 are not in operation and can be

left out of consideration. It is to be noted that the sound openings 6 may be provided with horns to amplify and direct the sound, or a separate casing having such horns may be mounted around the wall 5. In case of a single sound opening, which may or may not have a horn, the wall 5 together with the cover 7 may be made rotatable in order to permit variation of the direction of the sound.

10 In the embodiment shown in Figs. 4-6, the driving shaft 2 in addition to the blade wheel 10 carries a compressor wheel 11. Said compressor wheel is positioned at a certain distance from the blade wheel leaving a chamber 12 between it and the blade wheel. The blade wheel, the chamber 12 and the compressor wheel are all surrounded by a casing 14. The part of said casing surrounding the blade wheel is provided with a horn 15 leading from two sound openings 16, 17 in the casing. In the casing, between the chamber 12 and the blade wheel, is a partition 13 formed with a sector-shaped opening 18 adjacent the opening 16 in the circumferential wall of the casing, said opening 18 also extending somewhat beyond the edge of the opening 16, remote from the horn, as shown in Fig. 5. The casing 14 may either be stationary or rotatably adjustable about the shaft 2 to permit adjustment of the horn to the desired direction.

30 In operation, the compressor wheel 11 receives air through inlet openings in the casing and forces the air down into the chamber 12 which receives the air from all of the blades of the compressor wheel and acts as a storage chamber for the compressed air. As the pressure exerted by the compressed air upon the casing 14 gives rise to considerable friction due to the tendency of the air to rotate with the wheel 11, it is of importance to reduce said friction. To this end, the chamber 12 is surrounded by a wall 19 rigidly connected to the periphery of wheel 11 so as to rotate therewith. Between said wall 19 and the casing 14 there is a suitable packing 20 to prevent leakage of air. The compressed air stored up in the chamber 12 passes through the opening 18 in the partition 13 down to the blade wheel 10 which may be assumed to rotate in the direction of the arrow in Fig. 5. In this rotation, the blade wheel receives air in one of its blade spaces, before said space comes into communication with the sound opening and, as a result, a certain preliminary compression of this air will be effected, before the space reaches the sound opening 16 and allows the air to emerge therethrough. After the said space has passed the sound opening 16 and the blade following said space moves below opening 18 in the partition 13, the said space will still carry a certain amount of compressed air with it. This air is allowed to escape through the second sound opening 17. In order to promote the emission of the air through the opening 17 into the horn 15, the latter may be provided with a baffle 21 between the openings 16 and 17, said baffle being so shaped and arranged as to cause the air expelled through the opening 16 to produce a suction in the passage leading from the opening 17.

70 The air contained in the storage chamber 12 acts as a buffer during the operation, balancing the pressure shocks produced by the compressor wheel 11 and producing a substantially constant pressure above the outlet opening 18. Due to the fact that the blade wheel 10 is supplied with air already compressed, the blade wheel need not be made of such size as would otherwise be

necessary for a given final pressure on the air, as it emerges into the horn. In other words, the effect of the driving motor will be distributed to the two wheels 10 and 11 so that each of them performs a stage of the compression work.

5 In Fig. 6 is shown a blade wheel having sector-shaped blades like those shown in Fig. 3, with the exception that the blades are solid instead of hollow. It is well known to make the blades of sirens in the shape of very thin radial walls each 10 provided with an arc-shaped circumferential projection extending rearward with relation to the direction of rotation. In such a wheel is thus formed a pocket between each blade and its projection, and in said pocket air will be retained 15 and eddy currents will be produced, thereby reducing the efficiency of the wheel. In the blade wheels shown having sector-shaped spaces to receive the air, no such eddy current production and no retaining of air can take place. In such 20 a wheel the rear wall of the blade forms a guide wall for the compressed air, allowing it to emerge at high speed, as soon as said wall has passed beyond the rear edge of the sound opening 16. It is to be noted that, of course, said rear wall 25 need not be radial, as shown in the drawings, but may be arc-shaped in some suitable way.

Instead of a single horn, as shown in the drawings, several horns may be used, each leading from one or more sound openings in cooperation 30 with an inlet opening 18 for each horn. If it is desired to have several horns cooperate, it is necessary to take care that the emission through them takes place absolutely at the same time. In the spacing of the respective inlet openings 18 35 care must be taken that the distances the air must pass on its way from the various openings 18 to the outlet ends of the respective horns will be exactly the same, so that the emission of the sound from the various horns will take place exactly at the same time.

40 It is of importance to provide the best sealing possible between the blade wheel, the casing and the partition during the compression period. To this end, the clearances between the blade wheel 45 on the one hand and the casing and partition on the other hand may be reduced in the neighbourhood of the opening 18 and the horn 15 to the smallest value possible, as indicated in Fig. 5.

45 Due to the admission of air to a part of the blade wheel only at any given time it will be possible to avoid the heavy friction losses which in directed emission through one or a few outlets, would otherwise arise due to the fact that the blades when passing along those portions of the casing, where there are no sound openings, will carry compressed air with them, which will 50 produce a great friction as a result of its pressure upon the casing. It is to be noted, however, that it is impossible to prevent a certain amount of air of a pressure above atmospheric from being 55 carried by the blades during the passage of the blades below the unapertured portion of the partition 13. In order to overcome said drawback, a connection may be provided leading from the 60 corresponding portion of the casing to the inlet side of the compressor wheel 11, as shown in Figs. 7 and 8. In these figures the portion of the casing not occupied by the horn 15 is surrounded by a jacket 30 connected by ports 31 65 to the interior of the casing outside the blade wheel which leads to the space above the compressor wheel 11. The outlet end of the jacket may be shaped as an ejector, causing the compressor to exert a suction on the air contained 70 75

in the jacket 30, thereby promoting the evacuation of the parts of the blade wheel out of operation for the time being. This evacuation may, of course, be performed in a different way, without departing from the principle of the invention.

In the form shown in Fig. 9 the driving shaft 2 carries a compressor wheel 40 of radial flow type which delivers its compressed air to an annular channel 41 of successively increasing section of 10 passage bounded outwards and inwards by walls 42 and 43, respectively, carried by the compressor wheel. As shown, the wall 42 is connected to the wheel 40 by partitions 40' which form the operating blades of the wheel, while wall 43 is 15 directly connected to the wheel 40. The compressor wheel and the wall 42 are enclosed in a casing 44 having a partition 45 below the passage 41. Said partition 45 is formed with an opening 46 at its outer portion. Said opening 20 is of a limited peripheral length and of a radial length corresponding approximately to half the radius of the partition 45. Below the partition 45 is a blade wheel 47 provided with an annular air guiding surface 48 curved in conformity with 25 the curvature of the wall 43. The casing 44 is formed with a sound opening 49 from which leads a horn 50. In this case the channel 41 acts as a storage chamber for the compressed air produced by the compressor wheel 40.

30 By the use of a radial flow type of compressor a higher compression can be obtained than by the use of an axial flow compressor of the same dimensions, as in the first mentioned compressor the centrifugal force contributes to the compression. The air when escaping from the compressor wheel 40 into the diffusor channel 41 has a tendency to continue its rotation, particularly in the uppermost portion of the channel and, as a result, the air entering the passage 41 beyond 35 that edge of the opening 46 where the blades leave the opening on their rotation, must rotate almost through the entire circle before it reaches the opening 46 and is delivered to the blade wheel. In order to suppress this tendency, I provide inside the channel 41 at a certain distance from the said edge of the opening 46 a radial baffle 51 40 upstanding in the channel from the partition 45, said baffle, as shown in Figs. 10 and 11, being curved so as to divide the air, deflecting the air 45 striking the concave surface thereof back again towards the opening 46, while allowing the air 50 on the convex surface of the baffle to continue its rotation with the walls 42, 43.

In Fig. 12 is shown an apparatus like the one 55 shown in Fig. 7 but provided with means to evacuate the horn alternately with the emission of air therethrough. To this end, the horn 15 is formed with an enlarged chamber 52 at its inner end. Said chamber 52 opens both towards the blade 60 wheel 53 and towards a rotary valve 54 situated below the blade wheel and carried by the driving shaft 2 thereof.

The blade wheel comprises alternately sector-shaped blades and sector-shaped spaces open at 65 the periphery of the blade wheel. Said spaces are also open both at the top and bottom of the blade wheel. The valve 54 comprises a disk attached to the shaft 2 which is provided with an upstanding peripheral flange 55, having an 70 aperture right below each space of the blade wheel. Above the blade wheel 53 is a partition 56 in the casing 57 and below the blade wheel is another partition 58. The partition 56 is formed with an opening 59 of limited angular 75 extent to admit compressed air from the storage

chamber 60 to the blade wheel (see also Fig. 13), whereas the partition 58 presents an unapertured portion right below the opening 59 but is formed with an opening 61 in front of said unapertured portion, as seen in the direction of 5 rotation of the blade wheel (see also Fig. 14). The shaft 2 carries a compressor wheel 62 above the chamber 60. The casing 57 is provided with a jacket 63 surrounding the casing save the portion thereof occupied by the chamber 52. Said 10 jacket communicates with the interior of the casing by openings 64 situated outside the blade wheel.

In operation, when a space of the blade wheel is in communication with the chamber 60 through 15 the opening 59 and receives compressed air, said air will be forced out at high speed by the blade wheel into the chamber 52 of the horn to produce sound. At the same time communication between the chamber 52 and the interior of the 20 valve 54 is interrupted by an unapertured portion of the flange 55. When the chamber 52 is out of communication with any space of the 25 blade wheel, an aperture of the flange 55 brings about communication between the chamber 52 and the interior of the valve 54. By way of the opening 61 in the portion 58 and the inoperative spaces of the blade wheel the chamber 52 is in communication with the jacket 63 and is, consequently, subjected to a suction. By this means 30 the chamber 52 will alternately be subjected to pressure and to vacuum with resulting amplifying of the sound generation.

What I claim is:—

1. A siren having a rotatable shaft, a blade 35 wheel on said shaft and having an air outlet at its periphery, a casing surrounding said blade wheel formed with a sound opening in its peripheral wall, a horn carried by said casing and projecting radially therefrom and communicating 40 with said sound opening, and a wall in said casing covering an inlet face of the blade wheel, said wall having an eccentrically positioned opening for admission of air to only part of the cross-sectional area of the blade wheel, said casing and 45 said wall being rigidly connected to each other and mounted for rotary adjustment about said shaft so that the direction in which the horn extends may be changed by rotary adjustment of the casing and the air admission opening is 50 simultaneously correspondingly adjusted.

2. In combination, a siren having a rotatable shaft, a blade wheel on said shaft and having an air outlet at its periphery, a surrounding casing formed with sound emission openings, a valve to 55 control the admission of air to the blade wheel, a compressor wheel on said shaft, and a storage chamber for compressed air situated between said compressor wheel and valve for receiving compressed air from the compressor wheel and supplying the compressed air to the blade wheel 60 under the control of the valve.

3. In combination, a siren having a rotatable shaft, a blade wheel on said shaft and having an air outlet at its periphery, a surrounding casing 65 formed with sound emission openings, a valve to control the admission of air to the blade wheel, a compressor wheel on said shaft, a storage chamber for compressed air situated between said compressor wheel and valve for receiving compressed 70 air from the compressor wheel and supplying the compressed air to the blade wheel under the control of the valve, and a circumferential wall connected to said compressor wheel and surrounding said storage chamber.

4. In combination, a siren having a shaft, a blade wheel on said shaft and having an air outlet at its periphery, a surrounding casing formed with a sound emission opening, a horn leading from said opening for directing the sound, a wall covering the inlet of the blade wheel and having an opening for admission of air to a part only of the blade wheel at any given time, said last mentioned opening being situated immediately in advance of the sound opening and having a greater peripheral length than said sound opening.

5. A siren having a shaft, a blade wheel carried by said shaft and having an air outlet at its periphery, a casing surrounding said blade wheel and having a sound emission opening, a partition in said casing covering the inlet of the blade wheel and having an opening immediately in advance of said sound opening, the casing having an additional sound opening out of the range of the opening in the partition, and a horn leading from said two sound openings.

6. A siren having a shaft, a blade wheel carried by said shaft and having an air outlet at its periphery, a casing surrounding said blade

wheel and having a sound emission opening, a partition in said casing covering the inlet of the blade wheel and having an opening immediately in advance of said sound emission opening, the casing having an additional sound opening out of the range of the opening in the partition, and a horn leading from said two sound openings, said horn being formed with a separate passage for each of said sound openings, one of said passages being arranged to act as an ejector with respect to the flow of air through the other passage.

7. A siren having a shaft, a blade wheel on said shaft and having an air outlet at its periphery, a compressor wheel on said shaft, an air storage chamber between said compressor wheel and said blade wheel, a casing surrounding said blade wheel, said compressor wheel and said chamber, a partition in said casing in front of the inlet end of the blade wheel, said partition having an opening for admission of air to part of the cross sectional area of the blade wheel, said casing having a sound emission opening formed therein and a horn leading from said sound emission opening.

OLOF INGEMAR HARALD EKMAN.
